RETRACTILE ANTENNA MAST ASSEMBLY

Gillis E. Bader, Bellville, Tex.

Application May 13, 1949, Serial No. 93,137

3 Claims. (Cl. 189—15)

1

This invention relates to radio antenna or aerial masts, and more particularly to a retractile antenna mast assembly which can be mounted on the ground or other substantially horizontal supporting surface, and extended to any desired height, and can be raised and lowered, when desired.

It is among the objects of the invention to provide a light weight and simplified antenna mast assembly which can be based on the ground rather than on a roof or other elevated support, and will carry the antenna at an elevation as high or higher than the antenna would be carried by a roof-mounted mast structure, which mast assembly is easy and simple to assemble and erect, and can be placed in operative condition in a very short time for demonstrations and testing, which can be completely assembled, erected and repaired from the ground without the necessity of anyone climbing any part of the mast assembly or using a ladder, which is strong and wind resistant when erected, and may be quickly lowered, if desired, in the event of storms of unusual force, such as hurricanes and tornados, which can be operated from the ground to properly orientate and otherwise position the antenna for short-wave and television reception and which is economical to manufacture and neat and attractive in appearance.

Other objects and advantages will become apparent from a consideration of the following description and the appended claims in conjunction with the accompanying drawings, wherein:

Figure 1 is a vertical elevation of the antenna mast assembly in erected condition;

Figure 2 is a perspective view of a fragmentary top portion of the mast assembly showing the manner of mounting the antenna thereon;

Figure 3 is a transverse cross-section on the line 3—3 of Figure 2;

Figure 4 is a side elevation of a fragmentary portion of the mast assembly at an intermediate position lengthwise of the assembly showing the manner of attaching a guy wire to one side of the assembly;

Figure 5 is a view similar to Figure 4 showing the manner of attaching two guy wires to the opposite side of the assembly;

Figure 6 is an elevation on a somewhat enlarged scale of a fragmentary, intermediate portion of the antenna mast assembly, parts being broken away and shown in cross-section to better illustrate the construction thereof;

Figure 7 is an elevation of a fragmentary portion of the assembly below the portion illustrated in Figure 6;

2

Figure 8 is a longitudinal cross-section on the line 8—8 of Figure 7;

Figure 9 is a transverse cross-section on the line 9—9 of Figure 7;

Figure 10 is an elevation of a fragmentary lower portion of the assembly and a longitudinal cross-section of the assembly base;

Figure 11 is an elevation of a fragmentary, intermediate portion of the assembly;

Figure 12 is a longitudinal cross-section on the line 12—12 of Figure 11;

Figure 13 is a transverse cross-section on the line 13—13 of Figure 11;

Figure 14 is a diagrammatic view of the assembly in fully retracted condition, indicating in broken lines, a partially-erected condition of the assembly;

Figure 15 is a diagrammatic view of the assembly in partially-erected condition;

Figure 16 is a diagrammatic view of the assembly in fully-erected condition; and

Figure 17 is a transverse cross-section on the line 17—17 of Figure 6.

With continued reference to the drawings, the antenna mast assembly of the invention comprises, in general, a ground-engaging base 10, a derrick structure 11 pivotally connected at one end to the base 10 and adjustable thereon, a tubular guide 12 pivotally connected to the opposite end of the derrick structure, a tubular mast shaft 13 slidably received in the guide 12, antenna 14 on one end of the shaft 13, a socket 15 on the derrick structure 11 for receiving the opposite end of the shaft, a set of guy wires 16 connected to the derrick structure 11 at the guide-carrying end of the latter, a set of guy wires 17 connected to the shaft 13 between the guide 12 and the antenna 14, and, depending upon the length of the shaft 13, additional sets of guy wires, as exemplified at 18.

The base 10 is an elongated body of suitable material, such as wood or concrete, and is preferably set into the ground, so that it will be firmly held in position. Two spaced-apart ring bolts 19 and 20 extend through the base 10 with their bolt-receiving eyes or rings positioned just above the top surface of the base.

The derrick structure 11 is a ladder-like structure having a pair of side rails 21 and 22 which gradually converge from the wider, lower end to the narrow, upper end of the structure substantially symmetrical with the longitudinal center-line of the structure, and a plurality of spaced-apart, transversely-extending rungs or braces 23 secured at their opposite ends to the side rails 21 and 22 respectively.

Eye bolts 24 and 25 are secured in the ends of the side rails 21 and 22 respectively, at the wider, lower end of the derrick structure in position to lie between the ring bolts 19 and 20 secured to the base 10, and a rod or bolt 26 extends through all of the ring bolts to pivotally connect the derrick structure 11 to the base 10 for movement of the derrick structure between a substantially horizontal and a substantially vertical position.

An axle 27, having a semi-circular bend substantially at its mid-length location is secured to the tubular guide sleeve 12 substantially at the mid-length location of the latter, the guide sleeve being received in the semi-circular bend of the axle, and the axle extends, at its opposite ends, through apertures provided in the side rails 21 and 22 respectively, near the narrower, upper end of the derrick structure to pivotally connect the guide sleeve to the derrick structure for rotational or tilting movements of the guide sleeve about an axis which is substantially perpendicular to the longitudinal center lines of the derrick structure and of the guide sleeve 12.

Ring plates 28 and 29 are secured to the outer sides of the side rails 21 and 22 respectively, near the upper end of the derrick structure, one of these plates, for example, the plate 28 having two rings thereon and the alternative plate having a single ring. The set of guy wires 16 is secured at the upper ends to the rings of the plates 28 and 29, two wires being secured to the plate 28 and a single wire to the plate 29. The lower ends of these guy wires being disposed outwardly of the base 10 when the derrick structure is erected and spaced apart at substantially equal angular intervals of 120-degrees.

The tubular mast shaft 13 is slidably and rotatably received in the guide sleeve 12 and is a sectional structure made up of lengths of suitable metal tubing disposed in end-to-end relationship and secured together at abutting ends by suitable joint fittings as shown at 30 and 31. The joint fitting 30 comprises a structure such as a pair of curved, apertured plates receiving abutting end portions of two tube lengths constituting a part of the shaft 13, and a pair of bolts 32 extending through these plates and through the adjoining shaft sections or tube lengths respectively, near the abutting ends of the latter. This joint fitting provides a quick detachable fitting for the tube section immediately above the sections slidably received in the guide sleeve 12.

The joint fitting 31, and other joint fittings of the tubular shaft assembly, may be conventional, screw-threaded bushings or collars which may be positioned either outside or inside the tubular sections.

The antenna 14 may be of any usual or desired construction for the reception of particular broadcast signals, and constitutes no part of the present invention, except in the combination thereof with the supporting mast assembly. Such an antenna may comprise a stem 9, a "T" or cross-fitting 33 on one end of the stem and having one leg secured to the top of the stem, and a pair of arms 34 and 35 secured at their adjacent ends in oppositely-extending legs of the fitting 33 and carrying the antenna devices 14 at their outer ends. The end of stem 9 opposite fitting 33 is telescopically associated with the upper end of shaft 13 and may be secured by a through pin or other suitable device.

A stop collar 36 receives the shaft 13 below the fitting 33 and is held in adjusted position longitudinally of the shaft by suitable means,

such as the set screw 37 threaded through a screw-threaded aperture in the collar and bearing against the shaft, and a guy wire bracket 38 is rotatably mounted on the shaft immediately above the stop collar 36. This bracket comprises a tubular portion receiving the shaft 13, and three apertured lugs 39 extending radially outwardly from the tubular portion at substantially equal angular intervals of approximately 120-degrees. The guy wires of the set 17 may be connected at their upper ends to the lugs 39 respectively, and these guy wires are secured at their lower ends to the ground outwardly of the base 10 and at angular intervals of approximately 120-degrees.

If the third set of guy wires 18 is utilized, the stop collar 36 and bracket 38 assembly may be duplicated at a location along the shaft 13 above the attachment point of the wires of the set 18, and the lower ends of the wires of this third set of guy wires will be secured to the ground in the same manner outwardly of the base 10 and separated by substantially equal angular intervals of 120-degrees.

The socket 15 is a tubular body having an end wall 38 closing its bottom end, and a hook 39 secured to one side thereof and positioned to hook over any selected one of the transverse braces 23 near the bottom end of the derrick structure 11.

In assembling and erecting the device, with the derrick structure flat on the ground the wider end of this structure is placed on the base 10 with the ring bolts 24 and 25 on the derrick structure matching the corresponding bolts 19 and 20 on the base and the rod 26 is then extended through the registering eyes of the ring bolts to pivotally connect the derrick structure at its wider end to the base. The axle 27 is then installed on the narrower end of the derrick structure by placing the ends of the axles in the notches or apertures in the corresponding ends of the side rails of the derrick structure and securing the axle in position by suitable means, such as the bolts or pins 40 extending transversely through the side rails and across the notches therein between the axle and the adjacent ends of the side rails.

This disposes the guide sleeve 12 between the side rails for rotational movements about an axis disposed substantially perpendicular to the longitudinal center line of the derrick structure.

The tubular shaft 13 is now completely assembled except for the antenna assembly and one end to the smaller end of the derrick structure 12. The guy wires 16 are attached each at one end of the smaller end of the derrick structure and a line 41 comprising a twisted or braided copper wire cable is secured at one end to the tubular shaft 13, at the end of the shaft which has been passed through the guide sleeve 12. The tubular shaft 13 is then slid through the guide sleeve until the first joint collar or coupling 31 on the tubular shaft engages the normally upper end of the guide sleeve 12. By holding the tubular shaft 13 near the end thereof remote from the line 41 and using the shaft as a push pole with the coupling 31 limiting movement of the shaft through the sleeve 12, the derrick structure 11 can be brought to substantially vertical position.

The guy wires 16 are now made secure at their lower ends to hold the derrick structure in vertical position extending upwardly from the base 10. The antenna assembly 14 is now mounted

on the shaft 13 at the end of the latter remote from line 41 and the depending line 41 is pulled downwardly raising the antenna assembly and lowering the end of the shaft 13 to which the line 41 is connected until the shaft is substantially vertically disposed.

At this point clamp collar 42, having a radially-projecting, screw-threaded stem 43 is slid into the tubular shaft 13 and an orienting handwheel 44 is then slid onto the shaft and secured to the shaft, near the end of the latter to which the cable 41 is attached, by a suitable screw or pin 45 extending through the hub of the wheel and either piercing or contacting the tubular shaft 13. The tubular shaft 13 is then brought to a substantially vertical position and is slightly raised, so that its lower end can be dropped into the socket 15. An elongated slot 46 is provided in one of the braces 23 intermediate the length of the latter, and at the time the lower end of the tubular shaft 13 is dropped into the socket 15, the screw-threaded stem 43 of the clamp ring 42 is brought through this slot 46. A manually-rotatable nut 47, such as a wagon end-gate nut, is threaded onto the stem 43 and when tightened, will hold the tubular shaft 13 against rotation. The height of the antenna above the ground may be adjusted by selectively positioning the socket 15 on the transverse braces near the bottom end of the derrick and, if necessary, one or more tube lengths or tubular sections can be added to the lower end of shaft 13 after this shaft has been brought to substantially vertical position.

A pointer 48 is secured to one of the side rails, for example, the side rail 21, in alignment with the rim of the handwheel 44, and the handwheel is provided with indicia, such as compass points, as indicated in Figure 9, with which the pointer cooperates to indicate the direction at which the antenna 14 is set. With the nut 47 loosened, the wheel 44 can be manually rotated until properly positioned relative to the pointer 48, whereupon the nut 47 is tightened to clamp the tubular shaft 13 in the selected rotational position.

After the lower end of the tubular shaft is dropped into the socket 15, the copper cable 41 is carried down to the ground and connected to a suitable grounding device, such as a water pipe or a piece of metal driven deeply into the ground.

When it is necessary to work on the antenna, it is only necessary to raise the lower end of the tubular shaft 13 from the socket 15, removing the nut 47, and lower the upper end of the tubular shaft until the antenna is brought into convenient reach of a person standing on the ground, the guy wires attached to the tubular shaft, of course, being released for this operation. After the antenna has been repaired, the tubular shaft may be returned to its vertical position, its lower end dropped in the socket 15, the clamp collar stem 43 re-inserting through the slot 46, the nut 47 applied and the antenna wires re-connected to their ground connections. In order to completely collapse or retract the antenna mast, after the tubular shaft has been lowered, as indicated above, the guy wires supporting the derrick structure 11 are loosened and, using the tubular shaft as a pole, the upper end of the derrick structure is lowered until the entire assembly lies flat on the ground.

The invention may be embodied in other specific forms without departing from the spirit or essential characteristics thereof. The present embodiment is, therefore, to be considered in all respects as illustrative and not restrictive, the

scope of the invention being indicated by the appended claims rather than by the foregoing description, and all changes which come within the meaning and range of equivalency of the claims are, therefore, intended to be embraced therein.

What is claimed is:

1. A retractile antenna mast assembly comprising a fixed support, a first mast section secured at one end to said fixed support for movement about a substantially horizontal axis, a guide secured to said first mast section at its other end for swinging movements about an axis substantially parallel to said horizontal axis, a second mast section longer than said first mast section having its longitudinal center line substantially in a plane perpendicular to said axes and including the longitudinal center line of said first mast section, said guide engaging said second mast section for longitudinal sliding movement of said second mast section relative to said guide, an abutment carried by said second mast section intermediate the length thereof and bearing against said guide at one end of the latter to enable said second mast section to function as a push pole manually raising said other end of said first mast section to move the latter from a substantially horizontal position to an upright position, guy wires secured to said first mast section at said other end thereof supporting said first mast section in upright position, a strand depending from one end of said second mast section for manually pulling said one end downwardly and swinging said second mast section about the axis of movement of said guide to an upright position after said first mast section has been secured in upright position, said strand constituting a ground wire for the antenna mast, said second mast section being adapted to carry an antenna on the upper end thereof, socket means interconnecting said first and second mast sections at the bottom end of said second mast section after the latter has been moved to upright position supporting said second mast section in longitudinal alignment with said first mast section and in a selected position of longitudinal adjustment of the second relative to the first mast section, and a set of guy wires connected at one end to said second mast section near said other end of the latter supporting said second mast section in upright position.

2. A retractile antenna mast assembly comprising a fixed support, a first mast section secured at one end to said fixed support for movement about a substantially horizontal axis, a guide secured to said first mast section at the other end of the latter for swinging movements about an axis substantially parallel to said horizontal axis, a second mast section longer than said first mast section having its longitudinal center line substantially in a plane perpendicular to said axes and including the longitudinal center line of said first mast section, said guide engaging said second mast section for longitudinal sliding movement of said second mast section relative to said guide, an abutment carried by said second mast section intermediate the length thereof and engaging said guide at one end of the latter to enable said second mast section to function as a push pole for manually raising said other end of said first mast section to move the latter from a substantially horizontal to an upright position, guy wires secured to said first mast section at said other end thereof supporting said first mast section in upright position,

a strand depending from one end of said second mast section for manually pulling said one end of said second mast section downwardly about the axis of movement of said guide to an upright position after said first mast section has been secured in upright position, said strand constituting a ground wire for the antenna mast, said second mast section being adapted to carry an antenna on the upper end thereof, socket means interconnecting said first and second mast sections at the bottom end of said second mast section after the latter has been moved to upright position supporting said second mast section in longitudinal alignment with said first mast section and in a selected position of longitudinal adjustment of the second relative to the first mast section, and a set of guy wires connected at one end to said second mast section near said other end of the latter supporting said second mast section in upright position, said first mast section comprising a brace structure and said second mast section comprising a plurality of tube lengths joined together in end to end relationship.

3. A retractile antenna mast assembly comprising a fixed support, a first mast section secured at one end to said fixed support for movement about a substantially horizontal axis, a guide secured to said first mast section at the other end of the latter for swinging movements about an axis substantially parallel to said horizontal axis, a second mast section longer than said first mast section and having its longitudinal center line substantially in a plane perpendicular to said axes and including the longitudinal center line of said first mast section, said guide engaging said second mast section for longitudinal sliding movement of said second mast section relative to said guide, an abutment carried by said second mast section intermediate the length thereof and bearing against said guide at one end of the latter to enable said second mast section to function as a push pole for manually raising said other end of said first mast section to move the latter from a substantially

horizontal position to an upright position, guy wires secured to said first mast section at said other end thereof supporting said first mast section in upright position, a strand depending from one end of said second mast section for manually pulling said one end downwardly and swinging said second mast section about the axis of movement of said guide to an upright position after said first mast section has been secured in upright position, said strand constituting a ground wire for the antenna mast, said second mast section being adapted to carry an antenna mounted on the upper end thereof, socket means interconnecting said first and second mast sections at the bottom end of said second mast section after the latter has been moved to upright position supporting said second mast section in longitudinal alignment with said first mast section and in a selected position of longitudinal adjustment of said second relative to said first mast section, a set of guy wires connected at one end to said second mast section near the other end thereof supporting said second mast section in upright position, and hand operated means connected to said second mast section adjacent said socket means for imparting rotational movement to said second mast section while the latter is held in upright position.
